UNITED STATES PATENT OFFICE

CARL SCHLEMPER, OF OHLIGS, GERMANY

PILE WIRE AND METHOD OF MAKING THE SAME

Application filed March 4, 1927, Serial No. 172,741, and in Germany March 8, 1926.

My invention relates to a method of, and means for, securing a cutter blade in a holder of channel-section, and it is an object of my invention to provide a method and means for this purpose by which the blade is securely held against turning out of the channel.

To this end I forge a portion of the blade into a recess in the channel holder so that the parts are positively connected, and, in order to remove the blade, I flatten out the forged down portion so that it will not interfere with the motion of the blade.

In a preferred embodiment of my invention and which is particularly adaptable for securing blades in weaver's rulers or needles, in which an exchangeable blade is clamped between the flanges of a channel-section, the blade is heat-treated so that its metal partly remains unhardened and this soft spot is forged into a recess in one of the section flanges.

In this manner the blade is held against turning out in a very simple and efficient manner. The forging operation may be performed as desired, but preferably I employ a pair of pincers having two jaws one of which is provided with a punch and the other is normal. When it is desired to secure a blade in a holder, registering holes are made in its flanges, the blade is so inserted in the holder that its soft spot coincides with the two holes, and the punch of the pincers is forced into one of the holes, bending the metal of the blade at the soft spot and forging it into the hole on the opposite side. If it is desired to remove the blade the pincers may be reversed so that the metal which has entered the hole is forced out of it and the blade may be withdrawn. Preferably, however, I employ a separate instrument for removing the blade with a flat punch on one of its jaws, and a projection for keeping the jaws apart for a certain distance. The flat part is inserted in the hole into which the soft spot of the blade has previously been forged so that the metal is forced out of this hole, and the projection prevents the punch from entering too far and forging the bent metal into the opposite hole.

In the drawings affixed to this specification

and forming part thereof, a holder with the blade secured in it, and pincers for performing the several operations on the soft spot, are illustrated diagrammatically by way of example.

In the drawings,

Fig. 1 is an elevation of a blade holder at the end of a weaver's ruler or needle,

Fig. 2 is an elevation of a pair of pincers for securing the blade in its holder, and

Fig. 3 is a similar elevation of a pair of pincers for removing the blade from its holder.

The blade and the holder in Figs. 2 and 3 are shown in section on the line A—B in Fig. 1.

Referring now to the drawings, *a* is the shank of a weaver's ruler or needle to the end of which a holder *b* of channel-section is secured. At the outer end *c* of the holder, its flanges are connected, preferably by spot-welding. *d* is a blade which is inserted in the holder so that its pointed inner end is located against a bevelled face *e* at the inner end of the holder and that its soft spot is registering with two co-axial holes in the flanges of the channel one of which is indicated at *h* in Fig. 1.

A pair of pincers for securing the blade in the holder by forging its soft spot into one of the holes, is indicated at *f* in Fig. 2 and it will appear that one jaw of the pincers is provided with a punch *g*, which is preferably rounded on its operating face so that when the pincers are applied it will enter one of the holes and forge the metal of the soft spot into the opposite hole where it forms a boss *i* and the blade *d* is securely held against being turned out of the holder *b*.

Referring now to Fig. 3, *l* is a flat punch on one of the jaws of the pincers *k* for removing the blade, and *m* is a projection on the same jaw which maintains a given clearance between the jaws, and it will appear that in this manner the punch *l* is prevented from entering too far into the hole *h*, and extruding the metal into the opposite hole. At the same time the projection *m* serves for pulling the blade out of its holder *b* when it has been released.

I wish it to be understood that I do not desire to be limited to the exact details of construction shown and described for obvious modifications will occur to a person skilled in the art.

5 5 I claim:—

1. The process of securing an exchangeable blade in a pile wire provided with a holder of channel section, and of removing said blade from said holder, comprising hardening said blade except at one spot, providing opposite apertures in the flanges of said channel section, bending the metal of said blade at said unhardened spot into one of said apertures for securing said blade in said holder and bending it out of said aperture preparatorily to removing said blade from said holder.
- 10 15 20 25 2. A pile wire comprising a holder of channel section, each flange of said section having an aperture, and a hardened blade having a soft spot which is bent into one of said apertures so as to secure said blade in said holder.

25 In testimony whereof I affix my signature.
CARL SCHLEMPER.
